ATTORNEY

UNITED STATES PATENT OFFICE.

FRANK C. HINCKLEY, OF BRIDGEPORT, CONNECTICUT, ASSIGNOR, BY MESNE ASSIGNMENTS, TO COLUMBIA PHONOGRAPH COMPANY, INC., A CORPORATION OF NEW YORK.

SOUND REPRODUCER.

Application filed December 22, 1919. Serial No. 346,705.

To all whom it may concern:

Be it known that I, FRANK C. HINCKLEY, a citizen of the United States, residing at Bridgeport, in the county of Fairfield and 5 State of Connecticut, have invented certain new and useful Improvements in Sound Reproducers, of which the following is a full, clear, and exact description.

It is an object of my invention to improve sound reproducers by providing a new 10 form of pivotal support for the so-called stylus-bar of the reproducer and by so arranging the support that certain of the co-operating parts thereof shall also function 15 as housing means for the same. The pivotal support is such that it can be put under pressure without the use of springs and without at the same time materially, if at all, increasing the turning or rocking friction 20 on the pivotal means. This latter accomplishment is particularly important since it insures that little or none of the sound energy is lost in overcoming frictional resistance in or at the pivotal bearing. Other 25 objects will appear in the claims and in the detailed description taken in connection with the accompanying drawings in which:

Figure 1 is a plan or face view of the 30 reproducer with parts broken away and parts in dotted outline to more clearly show the hidden construction;

Fig. 2 is a section, taken on line 2—2 of Fig. 1;

Fig. 3 is an end elevation of the stylus-bar bridge showing the intermediate and 35 terminal knife edges as in the same straight line and in contact with their supports;

Fig. 4 is a view exposing the bridge, and, 40 Figs. 5 and 6 are sections, taken on lines 5—5 and 6—6, respectively, of Fig. 4.

Fig. 7 is a perspective view, showing in 45 complete assembly the various parts comprising the invention.

Like reference characters designate like 50 parts throughout the several views.

The casing of the reproducer or sound-box, includes a head member 10 and may be of any suitable configuration or outline, but which is illustrated in the form of a ring 55 having a peripheral diaphragm-surrounding portion. It is provided with a pair of abutments or supports 11, 12 for supporting the terminal knife edges 13, 14 of the bridge 15, to which latter is suitably connected the

upper and lower arms 17 and 16, respectively, comprising the stylus-bar proper. It is immaterial whether the bridge and arms be made as an integral whole or whether the parts be separately fabricated and subsequently mechanically united. The bridge is 60 provided intermediate its terminals with knife edges 18, 19 which are in substantially the same straight line as the terminal knife edges. For holding the bridge to its terminal supports 11, 12 and for putting pressure 65 on the bridge, there is provided a pair of axially adjustable posts 20, 21, one for each of the intermediate knife edges 18, 19. The posts are supported by a ledge 22 which, in the present instance, is a flanged extension of a plate 23 removably secured to the head 10. For illustrative purposes this plate is shown as being the front or face plate of the head, but, such showing is not to be taken as a limitation. To the back of the 70 head is secured a plate 24 which with plate 23 functions to secure a diaphragm 25 in the head. Back-plate 24 has a tubular projecting part 39 (see Fig. 2), having a bayonet lock, or other suitable connection, 75 to attach the sound-box to the tone-arm of the phonograph. This part has a tubular passage extending through it, and through back-plate 24—the top view of which is shown by numeral 40, in Fig. 1. If found 80 desirable the ledge 22 could be supported by or be a prolongation of said back plate 24. It will also be appreciated that said ledge could well be an integral or mechanical extension of the head 10 without departing 85 from the spirit of the invention. The main desideratum is that the ledge shall provide a comparatively rigid support for the posts 20, 21 to enable the latter to be held firmly against the intermediate knife 90 edges, it having been found that the reproducer functions more efficiently when the bridge is under pressure. The pressure on the bridge may be varied by adjusting the posts in their seats or nuts 26, 27, lock nuts 95 28, 29 serving to secure the posts in adjusted position. Of course, it is to be understood that the metal, or other resilient material, of the front plate 23 is such as to "give" or flex at the bend of the ledge 22, when the bridge with its bearing members is put under pressure. When the posts are thus 100 adjusted to bring about this pressure condi-

tion, the ledge 22 will have sprung away from the extension 30 of the back-plate 24, thus providing a space between the edges. By so disposing out of contact the free edge 5 of the ledge 22, forming the supporting means or apron, and the adjacent edge of the closure means formed by the extension 30 of the back-plate 24, the setting up of sympathetic vibrations in the adjacent parts, 10 and particularly from the ledge 22 to the extension 30 and back-plate 24, is prevented, thereby eliminating any interference with the sound transmitted. The back plate 24 has an extension 30, see Figs. 5, 6 and 7, 15 that closes the open side of the channel or trough within which it will now be seen that the bridge is located. The bridge is thus not only effectively housed and protected against external injury but the housing improves the appearance of the reproducer as a whole. It will be observed that 20 the nuts 26, 27 are each as wide as the space between the side walls of the housing. This feature is advantageous in that rotation of 25 the seats is prevented during the adjustment of the posts. The arm 16 has a boss 31 adapted to receive the thumb screw 32 that secures a stylus or needle 33, Fig. 1, therein; and the arm 17 is suitably secured 30 as at 34 to the diaphragm 25. The diaphragm is spaced from the plates 23, 24 by suitable cushion means as by rubber gaskets 35, 36 and the plates are suitably secured to the head 10 as by screws 37, 38. The 35 front plate 23 and the ledge 22 are suitably perforated to allow the arms 17 and 16 extending from the bridge 15 to function properly.

By having the back-plate 24 removable, 40 back-plates with different types of tone-arm attaching means may be employed. In this way, provision is made for standardization of the sound-box for use on tone-arms of different makes of recording or reproducing machines—it simply being necessary to substitute, for one back-plate, another having a different form of attaching means. The head 10 is preferably made of case-hardened steel for not only is a better anvil for the 45 terminal knife edges thus obtained, but also a maximum brilliancy of reproduction. It will be understood, of course, that while the specification describes the invention for use on a sound-reproducer, it may with equal 50 efficiency be applied to a sound-recorder. Therefore, the claims refer to the use of the invention on a sound-box, and it is understood that this term refers to both a reproducer and a recorder.

60 The preferred form of the invention has been shown and described in detail but, if desired, various changes in the form and proportion of parts can be made without departing from the spirit and scope of the 65 invention.

What I claim as new and desire to secure by Letters Patent is:

1. In a sound-box, the combination with a casing, and a stylus-bar, of a bridge carried by the stylus-bar, bearing means between the casing and bridge, a plate having a laterally-extending flange, said plate being secured to the casing with the lateral transverse edges of the flange free and non-resilient means carried by the laterally extending portion and meeting the bearing means whereby to put the bridge under pressure. 70

2. In a sound-box, the combination with a casing, and a stylus-bar, of a bridge carried by the stylus-bar, bearing means for the bridge, supporting means secured to said casing and extending laterally beneath the bridge, the lateral transverse edges of said supporting means being free, non-resilient means carried by the supporting means and having bearing with the bridge whereby to put the bridge under pressure, and closure means secured to the casing and terminating adjacent the supporting member. 80

3. In a sound-box, the combination with a casing, and a stylus-bar, of a bridge carried by said stylus-bar, bearing means for the bridge, laterally-disposed supporting means secured to said casing and extending laterally beneath the bridge, the supporting means having free, lateral transverse edges, a nut member seated on and non-turnably held by said supporting means, and a non-yieldable post adjustable in said nut having bearing with the bridge whereby to put the bridge under pressure. 95

4. In a sound-box, the combination with a casing, and a stylus-bar, of a bridge carried by the stylus-bar, bearing means between the casing and the bridge, a cover-plate secured to the casing, a ledge secured to said plate and extending laterally beneath the bridge, the ledge having free lateral transverse edges, and means carried by said ledge and having bearing with the bridge whereby to put the bridge under pressure. 100

5. In a sound-box, the combination with a casing, and a stylus-bar, of a bridge carried by the stylus-bar, bearing means between the casing and the bridge, a plate secured to said casing, a ledge secured to said plate and extending laterally beneath the bridge, the ledge having free lateral transverse edges, means carried by said ledge and having bearing with the bridge whereby to put the bridge under pressure, and a second plate secured to said casing and having a closure means terminating adjacent said ledge. 115

6. In a sound-box, the combination with a casing, and a stylus-bar, of a bridge carried by said stylus-bar, bearing means be- 120

tween the casing and the bridge, a plate secured to the casing, a ledge secured to said plate and extending laterally beneath the bridge, the ledge having free lateral 5 transverse edges, said plate having an opening through which the upper part or arm of the stylus-bar passes, said ledge having an opening through which the lower end of the stylus-bar passes, and means carried by 10 said ledge and having bearing with the bridge.

7. The combination as in claim 6, and a second plate secured to the casing and having an extension terminating adjacent the 15 ledge.

8. In a sound-box, the combination with a casing, a stylus bar, a bridge carried by the stylus-bar, a housing comprising side portions secured at the front and rear sides 20 of the casing and extending along the longitudinal sides of the bridge, and a lateral portion projecting from one of the side portions and extending beneath the bridge into adjacent relation with the other side 25 portion, and bearing means for the bridge, disposed within the housing, said bridge being supported by means including said lateral portion.

9. In a sound-box, the combination with 30 a casing, a stylus-bar, a bridge carried by the stylus-bar, a housing comprising side portions secured at the front and rear sides of the casing and extending along the longitudinal sides of the bridge, and a lateral portion extending beneath it, integrally formed along one longitudinal edge with 35 relation to one of the side portions, and free along its other longitudinal edge and its transverse edges, the longitudinal edge of the other side portion extending in proximity to said free longitudinal edge of the lateral portion, and bearing means for the bridge disposed within the housing, said bearing means being supported by said lateral portion.

10. In a sound-box, the combination with a casing having a pair of bearing supports separated by a gap, a stylus-bar bridge having its terminals seated in said supports, 50 housing means comprising side portions extending along the sides of the gap and closing it at both sides, and a lateral ledge portion supported by one of the side portions and extending beneath the bridge into adjacent relation to the other side portion, and means supported by the lateral portion projecting upwardly into bearing relation with the bridge.

11. In a sound-box, the combination with 60 a head member having a pair of spaced abutments, a stylus-bar bridge having bearing means engaging said spaced abutments, other bearing means, and removable diaphragm-retaining means supported by said head member and having a portion adapted

to engage said other bearing means, to support the stylus-bar bridge.

12. In a sound-box, the combination with a casing having a peripheral diaphragm-surrounding portion, of a stylus lever extending in front of said portion and a cross-bar carried by said stylus lever and disposed beneath said portion, a pair of bearing means interposed between the casing and the bar at its upper side, a pair of bearing means 70 provided upon the bar at its lower side, and at each side of the center and intermediate the said upper bearing means, said casing having a resilient projection, and means carried by said resilient projection engaging the bearing means at the lower side of the cross-bar, and adapted to maintain the bearing means at the upper side in engagement.

13. In a sound-box, the combination with 80 a casing having a peripheral diaphragm-surrounding portion, of a stylus lever extending in front of said portion and a cross-bar carried by said stylus lever and disposed beneath said portion, a pair of bearing means interposed between the casing and the bar at its upper side, a pair of bearing means 90 provided upon the bar at its lower side, at each side of the center and intermediate the bearing means at the upper side, said casing having a laterally bent portion, means engaging the bearing means carried by said laterally bent portion at the lower side of the cross-bar, and adapted to maintain it in engagement with the bearings at 95 the upper side.

14. In a sound-box, a diaphragm-carrying casing, a needle-arm support, removable means for holding a diaphragm in the casing provided with a depending apron, and bearing means disposed between the casing and the apron for pivotally mounting the needle-arm support, the diaphragm holding means adapted when removed to permit disengagement of the needle-arm.

15. In a sound-box, the combination of a casing, a stylus bar, bearing means between the casing and the stylus bar, a cover member secured to the casing having a portion depending at one side of the bearing means, and another portion bent laterally from the depending portion and extending beneath the bearing means, and rigid adjustable means carried by said laterally bent portion, and adapted to maintain the bearing in operative relation.

16. In a sound-box, the combination with a casing, of a stylus lever and a cross-bar carried thereby, bearing means at the lower side of the cross-bar, a laterally bent portion cooperating with the bearing means at the lower side of the cross-bar, bearing means at the upper side of the cross-bar, adapted to be maintained in engagement by said laterally bent portion, and a plate se- 125 130

- cured to the casing and having an extension terminating adjacent the laterally bent portion, to form therewith a housing for the bearing.
- 5 17. In a sound-box, the combination of a casing, a stylus bar, bearing means between the casing and the stylus bar, a cover member secured to the casing having a portion depending at one side of the bearing means, 10 and another portion bent laterally from the depending portion and extending beneath the bearing means, and having a central opening through which the end of the stylus bar projects, and rigid adjustable means 15 carried by said laterally bent portion and adapted to maintain the bearing in operative relation.
18. In a sound-box, the combination of a ring forming the side walls of a diaphragm 20 chamber, a diaphragm therein, a rear cover plate secured to the ring and adapted to support the diaphragm at its rear, a front cover plate secured to the ring and adapted to retain the diaphragm in the ring, a stylus bar 25 connected to the diaphragm, bearing means between the casing and the stylus bar, the front and rear cover plates having portions depending at each side of the bearing means, and a ledge portion bent laterally from one 30 of the depending portions into adjacent relation to the other and adapted to house and maintain the bearing means in operative relation.
19. In a diaphragm-retaining ring for a sound-box, a diaphragm-retaining portion 35 adapted to be secured to the casing of the sound-box, and an integral apron portion disposed at an angle to the retaining portion for supporting the bearings of the needle- 40 arm of the sound-box.
20. In a sound-box, a diaphragm-carrying casing, a needle-arm support, means for holding a diaphragm in the casing and provided with a depending integral apron, and 45 bearing means disposed between the casing and the apron for pivotally mounting the needle-arm support.
21. A sound-box including a casing having an annular portion, a plate at one side 50 of the annular portion having means to connect to a tone-arm, a retaining ring on the other side of the annular portion, a diaphragm held in the annular portion, the diaphragm being exposed by the retaining 55 ring, a ledge on the retaining ring, a stylus-bar having a bridge pivoted at its ends against the annular portion, and an adjustable bearing member carried by the ledge to pivotally mount the bridge and put it 60 under pressure.
22. In a sound-box, a casing, a stylus-bar, a bridge carried by the stylus-bar, bearing means between the casing and the bridge, a plate secured to the said casing, a ledge 65 on said plate and extending laterally be- neath the bridge, and a closure means terminating adjacent said ledge.
23. A sound-box including a casing, a stylus-bar, a bridge carried by the stylus-bar, front and back portions on the casing, 70 one having a lateral portion extending across the casing outwardly of its peripheral edge, said casing having a recess and the bridge on the stylus-bar extending into the recess and pivoted on the casing, the stylus-bar bridge being disposed between the peripheral edge of the casing and the lateral portion and being supported by the latter.
24. A sound-box including a casing, a stylus-bar, a bridge carried by the stylus-bar, front and back portions on the casing, 75 one having a lateral portion extending across the casing outwardly of its peripheral edge, said casing having a recess, the bridge on the stylus-bar extending into the recess and pivoted on the casing, adjustable posts operable through the lateral portion and engaging the bridge to hold it in position for pivotal movement under tension, and a closing part at one side of the bridge and extending between the peripheral portion of the casing and the free edge of the lateral portion.
25. In a sound-box, the combination with a casing, a stylus-bar, a bridge carried by the stylus-bar, a back plate and a front plate secured to the casing, one having a lateral portion extending transversely across the bridge, a part extending in the direction of the back plate adjacent to the lateral portion, and bearing means for the bridge between the lateral portion and the bridge.
26. In a sound-box, the combination with a casing, a stylus-bar, a bridge carried by the stylus-bar, a back plate and a front 100 plate secured to the casing, the front plate having a lateral portion extending beneath the bridge, a closing part extending into adjacent relation with the lateral portion to form a housing, and bearing means for the bridge disposed within the housing.
27. In combination, a diaphragm-enclosing member, a side member, a stylus-bar, and bearing members pivoting said stylus-bar on the diaphragm-enclosing member, 115 said side member being adapted to support and tension said stylus-bar in its bearings.
28. In a sound-box, the combination with a casing, of a needle-bar, bearing means between the needle-bar and the casing, supporting means beneath the needle-bar, and a companion bearing member between the needle-bar and the supporting means, said casing including an annulus, a closure plate at one side of the annulus provided with 120 means to connect to a tone-arm, and a securing member at the other side having a right angularly extending ledge carrying said supporting means.
29. A sound-box including a casing hav- 130

ing a tone-arm attaching portion, a diaphragm held in the casing, a needle-arm connected to the diaphragm and having a bridge pivoted against the casing, a spring 5 tension plate forming part of the casing and extended beneath the bridge, and means carried by the plate to pivotally mount the bridge in line with the aforesaid pivot mounting, and to hold it tensionally seated 10 at all times.

30. In a sound-box, a diaphragm-carrying casing, a needle-arm support, means for holding a diaphragm in the casing and provided with a bent apron, and bearing means 15 disposed between the casing and the apron for pivotally mounting the needle-arm support.

31. In a sound-box, the combination of a casing comprising a ring portion and a back 20 portion, a diaphragm mounted in the casing, cushion gasket rings within the casing engaging the diaphragm above and below at its edges, a retaining ring secured to the ring portion and engaging the upper gasket 25 under pressure to retain the diaphragm in place, the retaining ring having a downwardly extending portion provided with laterally bent arms, and being spaced from the lower end of the casing, a stylus lever 30 having a cross-bar disposed in the space between the casing and the arms, bearing

means upon the casing for the cross-bar, and bearing means upon the arms and engaging the cross-bar.

32. In a sound-box, a casing, a needle-bar, 35 bearing means on the casing, bearing means engaging the needle-bar and adapted to retain it in engagement with the bearing means of the casing, and a removable resilient diaphragm-retaining plate attached 40 to the casing and carrying the second-mentioned bearing means.

33. In a sound-box, a casing, a diaphragm, a stylus-bar having a pivot mounting on the casing, and an extension on the casing forming 45 a relatively stiff spring to hold the stylus-bar on its pivot mounting, and cooperating with the casing to house said mounting.

34. A sound-box comprising a casing and 50 a needle-arm with cross-bar pivotally carried thereon, a diaphragm retaining member on the casing, the cross-bar pivotally engaging the casing by means of bearings, means engaging bearings at the underside of the 55 cross-bar for supporting the same in position, the means being carried by an apron upon the diaphragm retaining member.

In testimony whereof, I affix my signature.

FRANK C. HINCKLEY.
